US00D793256S

(12) **United States Design Patent** (10) **Patent No.:** **US D793,256 S**
Iseli (45) **Date of Patent:** **** Aug. 1, 2017**

(54) **CASING FOR AN ELECTRONIC DEVICE**

(71) Applicant: **Elma Electronic AG**, Wetzikon ZH (CH)

(72) Inventor: **Marc Iseli**, Dürnten (CH)

(73) Assignee: **Elma Electronic AG**, Wetzikon (CH)

(**) Term: **15 Years**

(21) Appl. No.: **29/535,691**

(22) Filed: **Aug. 10, 2015**

(30) **Foreign Application Priority Data**

Feb. 11, 2015 (CH) 141287

(51) **LOC (10) Cl.** **10-04**

(52) **U.S. Cl.**

USPC **D10/75**; D10/76

(58) **Field of Classification Search**

USPC D10/46, 75, 76

CPC G01D 11/24; G01D 11/245; G01D 11/26

See application file for complete search history.

(57) **CLAIM**

The ornamental design for a casing for an electronic device, as shown and described.

DESCRIPTION

FIG. 1 is a perspective view showing my new design;

FIG. 2 is a front elevational view thereof;

FIG. 3 is a rear elevational view thereof;

FIG. 4 is a top elevational view thereof;

FIG. 5 is a bottom elevational view thereof;

FIG. 6 is a right elevational view thereof; and,

FIG. 7 is a left elevational view thereof.

The broken line showing of structural features in included for the purpose of illustrating non-claimed subject matter and forms no part of the claimed design.
